UNITED STATES PATENT OFFICE.

CHRISTIAN GANSLE, OF MEMPHIS, TENNESSEE.

DESIGN FOR A CROUSTADE.

Application filed March 21, 1925. Serial No. 12,801. Term of patent 14 years.

To all whom it may concern:

Be it known that I, CHRISTIAN GANSLE, a citizen of the United States, residing at Poplar Avenue and Kenilworth Street, in the city of Memphis, county of Shelby, and State of Tennessee, have invented a new, original, and ornamental Design for Croustades, of which the following is a specification, reference being had to the accompanying drawing forming part thereof.

Figure 1 is a plan view, Figure 2 is a perspective view, Figure 3 a lengthwise cross section, Figure 4 a crosswise cross section of a croustade showing my new design.

I claim:

The ornamental design for a croustade as shown.

CHRISTIAN GANSLE.
